UNITED STATES PATENT OFFICE

2,431,950

CORE CONSTRUCTION FOR ELECTRO-MAGNETIC APPARATUS

Leopold Mauerer, Chicago, Ill., assignor to Jefferson Electric Company, Bellwood, Ill., a corporation of Illinois

Application January 26, 1944, Serial No. 519,732

19 Claims. (Cl. 175—356)

1

This invention relates to improvements in core construction for electromagnetic apparatus and in particular to an improved clamping means which permits a core, such as a transformer or reactor core to be made in separate sections, and which exerts a clamping action on the core in two directions: laterally, to press the laminations together; and longitudinally, to hold the core sections in that closely abutting relationship which is desirable for establishing a satisfactory magnetic path.

An object of this invention is to provide a single clamping means for a sectional laminated magnetic structure which acts both laterally and longitudinally, and which serves not only to press the laminations of each section together, but to hold the sections in abutting relationship with each other.

A further object is to provide an improved core clamping means which bears laterally on each core section at or about the end thereof so as to minimize any tendency of the laminations to spread, as one section is forced into abutting engagement with another.

A still further object is to provide an improved core clamping means which bears on each section separately in a manner so as to provide a certain amount of lateral adjustment as the sections are forced into abutting relationship with each other.

Due to the closed circuit design of transformer cores, reactor cores and the like, it has been the practice to make each lamination in two pieces, and assemble them into the pre-wound coil, the layers of laminations being so arranged that the joints of adjacent layers are staggered. This provides a unitary core structure, and is referred to as one formed from interlaced laminations. The building up of such a core structure however is a time consuming task, and it is evident that the cost of assembling a transformer can be materially reduced if laminations of like shape can be stacked together in one section and laminations of another shape stacked together into a different section, and the two sections clamped together.

Practical objections to the adoption of such a construction arise from the fact that it is difficult to urge two sections into sufficiently intimate contact as to provide a core having a reluctance approaching that of a core formed from interlaced laminations. It has been found however that the use of such a sectional core in combination with the type of clamp herein described and shown gives eminently satisfactory results.

2

providing that the laminations are stamped to close tolerances. This is believed to be due in part to the use of a single clamp which acts in both directions so that the lateral pressure is increased gradually as the longitudinal pressure is increased. This gradual increase of pressure will permit the sliding or longitudinal displacement of one lamination with respect to an adjacent lamination so as to bring substantially all of the pairs of laminations into closely abutting contact, thereby reducing the reluctance of the core to a point where it approximates the reluctance of an interlaced core structure. It will be noted in this connection that the abutting relationship of a manually built up interlaced core structure is not perfect for the reason that each pair of laminations is not separately held in abutting relationship by any degree of pressure.

It is another object of this invention to provide an improved core construction wherein the core is built up in sections and the sections are assembled in abutting relationship and maintained therein in a manner to reduce the overall reluctance of the core to a minimum.

A further object is to provide a magnetic core assembly which, due to the relatively high longitudinal and lateral pressures exerted thereon, is not subject to any variation in the air gap between abutting sections, and is free from hum.

A still further object is to provide a sectional laminated magnetic core assembly in combination with lateral clamping means engaging each section separately so that the laminations of each section will be pressed together with substantially the same degree of pressure even though the sections may not be of identical thickness.

Other objects, features and advantages of this invention will become apparent as the description proceeds.

Reference is now made to the accompanying drawings which form a part of this disclosure, and in which like reference numerals refer to like parts:

Fig. 1 is an elevation of a preferred embodiment of this invention;

Fig. 2 is an end view of the unit shown in Fig. 1;

Fig. 3 is an enlarged detail of Fig. 2, which is partly in section;

Fig. 4 is an enlarged detail of Fig. 2;

Fig. 5 is a section taken along line 5—5 of Fig. 1;

Fig. 6 is an enlarged detail of Fig. 2 partly in section;

Fig. 7 is a modified form of this invention shown in elevation;

Fig. 8 is an end view of the transformer shown in Fig. 7;

Fig. 9 is an enlarged detail of Fig. 8, partly in section;

Fig. 10 is an enlarged detail of a modification, and

Fig. 11 is an end view of Fig. 10.

With reference now to Figs. 1 and 2, the reference numeral 15 designates generally a unit which is often referred to as a ballast. This unit is essentially a transformer together with two reactor coils, and is used in connection with gaseous conduction tubes. The ballast includes a primary and secondary coil 16 and two reactor coils 17 and 18. Suitable leads for these coils are shown. The transformer core 19 is composed of E-laminations 20 and I-laminations 21 which are interlaced, as shown in Fig. 2. The reactor core 22, for the reactor coil 17, is formed of E-laminations 23, and the reactor core 24, for the reactor coil 18, is formed solely from E-laminations 25. It will be seen that the transformer core 19, and reactor cores 22 and 24 comprise three separate sections which are held in end to end relationship, there being a butt joint 26 between the cores 19 and 22, and a butt joint 27 between the cores 19 and 24.

These separate sections are held in end to end relationship by means of clamps 28 and 29. Inasmuch as these clamps are identical to each other, only clamp 28 will be described in detail.

Clamp 28 comprises a strap 30, end pieces 31 and 32, and spacers 33. The strap 30 is tensioned around the three core sections and at its ends is provided with bolts 34 and 35 which may be suitably secured to the straps by welding. The end piece 31 is in the form of a channel, and the bolts 34 and 35 pass through certain apertures which have been formed in the connecting or web portion of the channel by striking out lips 36 and 37. The outer ends of the bolts are engaged by nuts 38 and 39 which react against the connecting portion of the channeled end piece 31. It will be noted in Fig. 3 that the bolts 34 and 35 are disposed at an angle to each other and that the connecting portion has been formed to provide two angularly disposed portions 40 and 41, the plane of each of these being perpendicular to the axis of the bolts 34 and 35 respectively, so as to form a seat for the nuts 38 and 39.

The end piece 32 is also in the form of a channel whereof the connecting portion has been cut away to form edges 42 and 43, around which edges the strap 30 is bent.

The spacers 33 are disposed along each leg of the strap at points opposite the butt joints 26 and 27. The spacers are identical in construction, and each is provided with feet 44 and 45 which are disposed at an angle to each other so that as shown in Fig. 4, foot 44 will bear against the reactor core section 22, and foot 45 will bear against transformer core section 19. The spacers are rockingly mounted on the strap 30 by means of lugs 46 and 47 which are struck up and around the strap 30. The edges of the strap 30 may be notched as shown (at 48) in Fig. 5 so as to provide an interlocking engagement with the lugs 46 and 47, thereby maintaining the spacers 33 in their proper position opposite their respective butt joints.

In operation, after the coils have been assem-

bled with respect to the core sections, they are placed in end to end relationship, and the clamps 28 and 29 are slipped over the assembled unit. As the nuts 38 and 39 are tightened, the bolts 34 and 35, and the strap 30 will be drawn up which will have a dual effect of urging the core sections into intimate relationship with each other at the butt joints 26 and 27, and of pressing the laminations of each section together laterally. There may be slight irregularities in the alignment of the laminations of one stack or core section with the laminations of another stack, which irregularities, as the strap is tightened up, may cause a slight lateral shifting of one core section with respect to another. This lateral shifting is permitted by means of the rocking mounting of the spacers 33 on the strap 30.

It will be noted that the edges 42 and 43 of the end piece 32 are offset inwardly beneath the extended surface plane of the core section 24. This construction is shown in detail in Fig. 6. This permits the strap to contact the corner of the core section 24 so that the laminations will be pressed together at their lower edge, just as they are pressed together at their upper edge by the feet of the spacers 33. This same effect is secured with respect to the end piece 31 by means of the lips 36 and 37 which tend to determine the position of the bolts 34 and 35. Inasmuch as the bolts do not possess a flexibility comparable to that of the strap 30 which can actually be bent around the lower corner of the reactor core section 24 to a slight extent, the lips 36 and 37 are slightly resilient so that they may give slightly to permit the proper angular alignment of the bolts with the legs of the strap 30.

It will be noted that the edges of the side members of the channeled end pieces 31 and 32 bear against the lamination stacks and serve to align them as the nuts 38 and 39 are being tightened. In other words, if, in the original stacking, the edges of the laminations are not even, these irregularities will tend to be straightened out as the straight edges of the end pieces are brought to bear against the laminations with considerable pressure.

A modified form of this invention is disclosed in Figs. 7 to 10 inclusive, and comprises an ordinary transformer designated by the reference numeral 50. The transformer comprises a primary and secondary coil 51, and a core 52. The core is not made of interlaced laminations, as is the core 19 of Figs. 1 and 2, but consists of two sections, an I-section 53 and an E-section 54. Each section is merely a stack of laminations of identical size and shape. The two sections are held in abutting relationship by means of clamps 55 and 56 which are substantially identical. Only clamp 55 will be described herein.

This form of clamp comprises a strap 57 in the form of a loop, the ends being spot welded to each other as shown at 58. End pieces 59 and 60 are disposed between the ends of the core and the strap, the end pieces providing straight edges for the proper alignment of the separate laminations as described in connection with Figs. 1 to 6.

Each of the end pieces consists of a channel member in which the connecting or web portion is disposed in contact with the core, and the edges of the said pieces contact the strap 57. End piece 59 receives wedges 63 and 64, the former sliding on the web portion of end piece 59, and the latter being confined between the strap 57 and the wedge 63. It will be seen that as these wedges are forced into place, the strap 57 will

be tensioned. Spacers 61, identical to the spacers 33, are provided, one pair of which straddles the butt joint between the core sections 33 and 54 as shown in Fig. 8. The other pair of spacers engages section 54 at an intermediate portion to prevent buckling.

In the modification herein disclosed, the strap 57 is apertured as indicated at 62, and the end piece passes through the aperture. In this particular instance the spacing between the apertures determines the points at which the strap will be bent, this spacing being such that a portion of the strap is disposed diagonally with respect to the surface of the top and bottom laminations, as shown in Figs. 8 and 9, and serves to compress the stacks together at their edges.

It will be seen that in both of the preferred embodiments of this invention herein shown, that the clamp acts in two directions; that is, it compresses the laminations, and it urges the core sections in intimate engagement with one another. In the reactor unit of Figs. 1 to 6, a spacer may be inserted in the butt joints 28 and 27, if desired, the spacer being of suitable nonmagnetic material, to increase the air gap effect; however, it will be noted that the middle legs of the reactor cores 22 and 24 terminate short of contact with the transformer core 19, thereby providing an air gap which introduces the desired reluctance in the reactors without resorting to the insertion of the spacers.

A further modified form of means for tightening up the clamp is shown in Figs. 10 and 11. The strap 70 is provided with free ends 71 and 72, each of which is apertured to receive a wedging member 74. An end piece 73, similar in form to the end piece 32, is interposed between the wedging member 74 and core 11. The wedging member is so shaped that it presents cam surfaces 75 at either end, which rise as one approaches the middle of the wedging member 74. Inwardly adjacent to these cam surfaces 75 are arcuate portions 76, the radius of which approximates the distance between the arcuate surface and the corner 78 of the core around which the ends 71 and 72 may be bent.

In assembling, after the strap 70 has been positioned around the core 11, the end piece 73 is inserted between the end portions 71 and 72, and then these end portions may be spread sufficiently so that the ends of the wedging member 74 may be inserted in the apertures provided therein. Then as the end portions 71 and 72 are forced toward each other, the strap will be progressively tightened until the high point of the cam surfaces 75 are reached. Further forcing of the end portions 71 and 72 toward each other will cause the strap to be bent around the corners 78 of the core 11, thereby causing a clamping action to be exerted on the end of the core. Inasmuch as the surfaces 76 are arcuate with the corners 78 as a center, there will be no tendency for the end portions 71 and 72 to straighten out, but it will be noted that this arcuate portion does resist any tendency of the ends to spring outwardly in a lateral direction, as contrasted with a rotational movement. Thus the clamping means is effectively locked.

Although only preferred embodiments of this invention have been described and illustrated herein, it will be understood that various modifications and changes may be made without departing from the spirit of this invention. The drawings and the foregoing description are illus-

trative only, and this invention is defined only by the appended claims.

The term "transformer core" as used in the appended claims is intended to indicate generally the core of any electro-magnetic apparatus, whether it be designed specifically for use as a transformer, a ballast, a reactor, or other type of apparatus.

I claim:

1. A transformer core comprising a plurality of sections, each section consisting of a stack of laminations, and clamping means surrounding said core to maintain said sections in abutting relationship, said clamping means including a tensioned strap and spacer members disposed between said strap and the top and bottom laminations of each core section at points adjacent the joint therebetween to compress said laminations laterally, said spacers each having two bearing points, one of said points bearing against the laminations of one core section and the other bearing against the laminations of the other core section, thereby preventing spreading of the laminations at the abutting edges of each stack.

2. A transformer core comprising adjacent sections, each section consisting of a stack of laminations, a tensioned strap surrounding said core and maintaining said sections in end to end relationship, and spacer members disposed between said strap and said core and having two separate bearing surfaces, each of which bears on one of said adjacent sections at points adjacent the joint therebetween to compress said laminations laterally.

3. A transformer core comprising adjacent sections, each section consisting of a stack of laminations, a tensioned flexible member surrounding said core and maintaining said sections in end to end relationship, and a spacer member mounted on said tensioned flexible member and having two points of engagement with said core, and disposed so that said points of engagement bear against the top laminations of adjacent sections.

4. A transformer core comprising adjacent stacks of laminations, and clamping means surrounding said core and maintaining said sections in abutting end to end relationship, said clamping means including a tensioned strap and spacer members disposed between said strap and said core at points opposite the joints between adjacent stacks, said spacers having two separate points of engagement, one for each of said adjacent stacks, so that each spacer bears on both of said adjacent stacks to compress said laminations laterally.

5. A transformer core comprising adjacent stacks of laminations, and clamping means surrounding said core and maintaining said sections in abutting end to end relationship, said clamping means including a tensioned strap and spacer members rockingly mounted on said strap and having two points of engagement with said core, and disposed so that said points of engagement bear against adjacent stacks whereby a slight lateral adjustment of the stacks may be effected as the strap is being tensioned.

6. A transformer core comprising two laminated core sections disposed in abutting relationship, a strap disposed around said core sections, a spacer disposed between said strap and the top lamination of one of said sections, and a second spacer disposed between said strap and the bottom lamination of said section at a point substantially opposite said first mentioned spacer, both of said spacers being rockingly mounted on

said strap, and means to tension said strap to force said two sections together and to compress the laminations between said spacers.

7. A transformer core comprising two laminated core sections disposed in abutting relationship, a strap disposed around said core sections, two spacers disposed between said strap and said core sections and each bearing on both of said sections at oppositely disposed points, end pieces disposed between said strap and the ends of said core and bearing edgewise on the laminations of each of said sections, so as to cause sliding longitudinal displacement of a projecting lamination with respect to an adjacent lamination when said strap is tensioned, and means to tension said strap so as to cause said laminations to be compressed gradually, thereby permitting edgewise adjustment of said laminations with respect to said end pieces before said strap has been tensioned to any great extent wherein said laminations are clamped together with a force sufficient to prevent further displacement thereof.

8. A clamp for a laminated transformer core comprising a strap disposed around the core, and an end piece interposed between said strap and the edges of the laminations of said core, said strap being tensioned around said end piece so that it engages the corners of said core to compress said laminations, and said end piece being extended beyond said strap so as to engage the edges of all of said laminations.

9. A clamp for a laminated transformer core comprising a strap in the form of a loop surrounding said core, an end piece interposed between said strap and the edges of the laminations of said core, said strap being disposed around said end piece in such a manner that it engages the corners of said core to compress said laminations, and said end piece being extended beyond said strap so as to engage the edges of all of said laminations, and cooperating wedges bearing on said end piece and on said strap for tensioning said clamp.

10. A clamp for a laminated transformer core comprising a strap disposed around the core, an end piece in the form of a channel bearing on the edges of the laminations of said core, the opposite walls of said channel being perpendicular to the end surface of said core, said strap being bent around said end piece so that it engages the corners of said core to compress said laminations, and said end piece being extended beyond said strap so as to engage the edges of all of said laminations, and cooperating wedges slidingly disposed within said channel and confined between the opposite walls thereof whereby said strap may be tensioned by sliding one wedge over the other.

11. A clamp for a sectional laminated transformer core comprising a U-shaped strap having threaded bolts secured to the free ends thereof, an end piece for cooperation with the open end of said strap and having apertures formed therein to receive said bolts, and nuts threaded onto said bolts and bearing against said end piece to tension said strap and to draw said end piece against the edge of said laminated core to align the laminations thereof, in combination with a spacer disposed between the strap and the core, said spacer bridging the joint between the sections of the core, and having two separate bearing points, one bearing on each section.

12. A clamp for a laminated transformer core comprising a U-shaped strap having threaded bolt portions secured to the free ends thereof, an

end piece in the form of a channel for cooperation with the open end of said strap, said channel having a web portion spaced from the edges of said laminations and having apertures formed in said web portion to receive said bolt portions, said apertures being offset inwardly from the extended side surface planes of said core whereby said bolt portions are disposed at an angle to said planes and engage said core at its corners to compress the laminations thereof.

13. A clamp for a laminated transformer core comprising a U-shaped strap having threaded bolts secured to the free ends thereof, an end piece in the form of a channel for cooperation with the open end of said strap, said channel having a web portion spaced from the edges of said laminations and having apertures formed in said web portion to receive said bolts, and resilient lips formed on said end piece and spaced from each other by a distance slightly less than the thickness of the core plus the bolts, and engaging said bolts to hold the same against spreading, and to maintain them in contact with the corners of said laminated core.

14. A clamp for a laminated transformer core comprising a strap adapted to be slipped over the core, and spacers secured to said strap for engaging the outer laminations of said core, said spacers being provided with two feet adapted to engage said core, and having lugs struck up from the connecting portion between said feet and embracing said strap.

15. A clamp for a laminated transformer core comprising a strap adapted to be slipped over the core and having notched edge portions, and spacers secured to said strap for engaging the outer laminations of said core, said spacers being provided with two feet adapted to engage said core, and having lugs struck up from the connecting portion between said feet and embracing said strap at said notched portions in interlocking relationship.

16. In a sectional laminated core structure for electromagnetic apparatus, clamping means for compressing said laminations and for urging the separate sections of said core structure in flux transmitting relationship, said clamping means comprising a strap provided with spacer members engaging each section separately at points adjacent the joint therebetween, and end pieces disposed at opposite ends of said core structure and engaging the several laminations thereof, said strap being tensioned around one of said end pieces, and a wedge shaped tensioning device bearing against the other of said end pieces and engaging said strap for tensioning the same, said strap, at those portions thereof extending from a spacer member to one of said end pieces, being disposed at an angle to said laminations in such a manner as to engage the corners of said core structure and to compress said laminations.

17. A tensioning device for a core clamp which includes a strap disposed around two sides and an edge of a laminated core, the ends of said strap extending beyond the opposite edge thereof, said tensioning device comprising a transverse member disposed parallel to said opposite edge of said core and reacting thereagainst, the ends of which member are received in oppositely disposed apertures formed in said strap, said transverse member including a cam surface engaged by said apertured strap, said cam surface being continuous and comprising a rise portion and a dwell portion whereby said strap will remain in a ten-

sioned condition after it has been bent around a corner edge of said core.

18. A tensioning device for a core clamp which includes a strap and a spacer interposed between said strap and the side of a laminated core, said tensioning device comprising a transverse member disposed at an edge of said core and reacting thereagainst, the ends of which member are received in oppositely disposed apertures formed in said strap, said transverse member including 10 a cam surface engaged by said apertured strap which has a high point with respect to said spacer and a descending portion inwardly adjacent thereto, all points on said descending portion being substantially equidistant from the nearest corner edge of said core to permit said strap to be bent around said corner edge without substantially varying the tension thereon.

19. A clamp for a laminated sectional core to be used in electromagnetic apparatus, comprising 20 a U-shaped strap disposed about the core, the free ends of which extend beyond one edge of said core and are provided with perforations, and tensioning means for said strap comprising a member disposed parallel to said edge of said core and having ends adapted to be received within said perforations in strap engaging relationship, the remote portions of said ends being wedge shaped and each having a high point so as to cause said strap to be tensioned as the perforated portions thereof are forced together toward said high points, and the portions adjacent to said high points of said end member arcuately shaped with respect to the nearest corner of said core

as center, whereby further forcing together of said free ends will cause said strap to be bent around said free ends, the length of said adjacent arcuate portions being sufficiently great so as to permit the bending of said strap beyond its elastic limit whereby it will be locked in tensioned position.
